Primary Examiner — Carol P Rademaker(74) *Attorney, Agent, or Firm* — Mayback & Hoffman, P.A.; Gregory L. Mayback(57) **CLAIM**

The ornamental design for a box, as shown and described.

DESCRIPTION

FIG. 1 is a top, front perspective view of a box according to the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines showing a central portion of the bottom surface are included for the purpose of illustrating environmental structure and forms no part of the claimed design.
